M. W. MOESTA

SPOT WELDING MACHINE

Filed Oct. 17, 1927

Inventor
Marvin W. Moesta

Attorney

UNITED STATES PATENT OFFICE.

MARVIN W. MOESTA, OF DETROIT, MICHIGAN.

SPOT-WELDING MACHINE.

Application filed October 17, 1927. Serial No. 226,539.

The present invention pertains to a novel portable spot welding machine of such construction that both electrodes may be carried from place to place and applied to the work wherever desired. Further, the invention includes an electrode retracting and attracting device which is operable and controlled by one of the hands of the operator supporting the machine.

10 The new construction is an improvement over that shown in my Patent No. 1,548,204 of August 4, 1925, inasmuch as the latter includes a permanently fixed electrode and movable electrode, while the new device is characterized by both electrodes being supported in a portable carrier, with one of the electrodes movable relatively to the other. The movable electrode is adjusted relatively to the fixed member by the means mentioned 20 above.

The invention further includes a cooling system for the conductors and electrodes similar in principle to that shown in my Patent No. 1,548,204. Cooling tubes are applied 25 to both conductors and connected to both electrodes and are further connected to each other so that a circulation of the cooling medium is maintained.

30 The invention is fully disclosed by way of example in the following description and in the accompanying drawing, in which—

Figure 1 is an elevation of the device partly in section;

Fig. 2 is a section on the line 2—2 of Figure 1;

Fig. 3 is a section on the line 3—3 of Figure 1;

Fig. 4 is a detail vertical section showing the valve in exhaust position; and

40 Fig. 5 is a similar section showing the valve in intake position.

Reference to these views will now be made by use of like characters which are employed to designate corresponding parts throughout.

45 The machine is built upon a frame or carrier consisting of a cylinder 1 having bosses 2 and 3 formed at diametrically opposite points thereof. In the upper boss is fitted, an insulation sleeve 4, held by screws 4', which receives a metallic electrode 5. The member 5, as shown more clearly in Figure 3 has an interior longitudinal chamber 6 into which is fitted an axial tube 7. A cable conductor 8 is fitted into the rear end of the electrode 5 and is formed with a head 9 whereby it is anchored in the electrode. The electrode

is again chambered as at 10 around the conductor and terminates in a nipple 11 which is spaced from the conductor. An insulation tube 12 is applied over the nipple and secured thereto by a band 13. The tube 12 is spaced around the cable and extends for a considerable distance along the same. A passage 14 is drilled longitudinally of the electrode and connects the chambers 6 and 10.

60 In the remaining sleeve 3 is fitted a bronze sleeve 15, held by a screw 15', which provides a suitable wear surface for a cylindrical electrode holder 16 having fixed therein a chambered electrode 17 similar to the electrode 5 already described. It will be seen by reference to Figure 1 that the electrode 17 is equipped with a cable conductor 18 and a surrounding conduit 19. The interior construction of the electrode 17 is the same as that 70 of the electrode 5. Elbows 20 are threaded through the electrodes to communicate with the rear ends 21 of the tubes 7 which are closed by the body of the electrodes. The two elbows are joined by a hose or similar tubular 75 member 22 as shown more clearly in Figure 2.

This construction provides for a circulation of a cooling medium through the conduits 12 and 19 and the electrodes 5 and 17. If for example water under pressure is supplied to 85 the tube 12, it will pass from the chamber 10 through passage 14 to the chamber 6 and will not enter the inner tube 7 until running substantially the entire length of the chamber 6. It will then flow through elbows 20 and coupling 22 to the electrode 5, where it will follow a course opposite that described and will finally be discharged through the conduit 19.

80 A terminal 23 is fitted into the electrode 17 preferably in alignment therewith. Another terminal 24 is threaded into the electrode 5 preferably at right angles thereto and terminating in a tip 25 in alignment with the terminal 23. The members 23 and 25 may be spaced as shown in Figure 1 to permit insertion of the work therebetween.

90 The cylinder 1 and sleeve 3 are formed with a common slot 26 extending partially along their length for the purpose of accommodating a lug 27 extending from the slideable holder 16. In the cylinder is mounted a piston 28 having the lug 27 received in the wall thereof. The piston is maintained under the pressure of a spring 29 which tends to retract the piston and holder 16 from the 100 terminal 24 to the position shown in Figure 1. The forward wall of the cylinder has a

vent 30 which permits discharge of air from the cylinder when the piston wall approaches this forward wall.

A valve casing 31 is cast integral with the cylinder 1 and is formed with a cylindrical chamber 32 as shown in Figures 4 and 5. The chamber contains a valve consisting of a stem 33 carrying heads 34 and 35 spaced by a neck 36. The casting 31 has a boss 37 formed behind the piston and communicating with an air supply pipe 38. A duct 39 is drilled through the casting to connect the interior of the boss with the valve chamber 32. Another duct 40 is drilled through the cylinder wall to establish communication between the valve chamber and the cylinder. The size and spacing of the ports 39 and 40 are such that the ports may be bridged by the neck 36 to establish communication between the air pipe 38 and the cylinder. The valve casing 31 has an exhaust port 41, the location of which is such that the stem 36 will permit communication between it and the port 40 when the head 35 covers the port 39 as shown in Figure 4. A pin 42 fixed in the valve casing and engageable by the inner ends of the heads 34 and 35 prevents movement of the valve member beyond the positions described with reference to Figures 4 and 5 and illustrated therein.

The stem 33 is extended lengthwise of the cylinder 1 and is guided in an ear 43 formed at the forward end of the cylinder. The extremity of the stem is in the nature of a button 44 which is so positioned between the sleeves 2 and 3 that it may be engaged by at least one of the hands holding the sleeves. A spring 45 attached at one end to the stem 33 and having its other end bearing against the casing 32 normally moves the valve to the position shown in Figure 4.

This position of the valve connects the cylinder with the exhaust port 41 and obstructs the inlet port 39, so that the spring 45 is free to retract the piston 28 and movable electrode 17 to the position shown in Figure 1. The tool may now be positioned so that the area

to be welded will be received between the terminals 23 and 24. The rod 33 is now pushed inwardly by one of the fingers of the operator whereby the valve is carried to the position shown in Figure 5. The air supply port 39 is now in communication with the cylinder port 40 and the exhaust port 41 is obstructed by the head 34. The compressed air which enters this cylinder moves the piston forwardly so that the terminal 23 is brought into engagement with one surface of the work while the tip 25 engages the other surface. Current is now supplied to the terminals by any suitable switching device which may function automatically on adjustment of the valve. In fact the source of current may be permanently connected to the cables 8 and 18 so that the circuit will be completed only when the members 23 and 25 engage the object to be welded.

Although a specific embodiment of the invention has been illustrated and described, it will be understood that various alterations in the details of construction may be made without departing from the scope of the invention as indicated by the appended claims.

What I claim is:

1. In a portable spot welding machine, a cylinder, a fixed electrode and a movable electrode carried thereby, a piston slidable in said cylinder and connected to the movable electrode, a valve controlling the flow of pressure fluid to and from said cylinder, and a control element adapted to actuate said valve.

2. A portable spot welding machine comprising a carrier consisting of a cylinder and electrode holders, a fixed electrode mounted in one of said holders, a movable electrode supported by the other holder, a piston slidably in said cylinder and connected to said movable electrode, a valve controlling flow of pressure fluid to and from said cylinder, and a control element adapted to actuate said valve.

In testimony whereof I affix my signature.
MARVIN W. MOESTA.
